UNITED STATES PATENT OFFICE.

WILLIAM O. BARNES, OF LEOMINSTER, MASSACHUSETTS.

MACHINE FOR GRINDING FORMED CUTTERS.

1,373,586.

Specification of Letters Patent.

Patented Apr. 5, 1921.

Application filed October 25, 1919. Serial No. 333,161.

To all whom it may concern:

Be it known that I, WILLIAM O. BARNES, a citizen of the United States, residing at Leominster, county of Worcester, State of Massachusetts, have invented an Improvement in Machines for Grinding Formed Cutters, of which the following is a specification.

This invention relates to grinding machines, and especially, although not exclusively, to machines for grinding formed cutters, the same being in the nature of an improvement on the device shown and claimed broadly in Letters Patent Nos. 1,196,420 and 1,236,898, issued to me August 29, 1916 and August 14, 1917, respectively.

The present invention has for its objects to provide an improved machine for grinding the profile faces of the teeth of irregularly formed cutters or similar irregular profiles, particularly those having curves of very small radius or sharp internal angles, to provide means for grinding off the back portion of the profile face of a tooth for reducing the width of said face when desired, and also to provide an improved wheel dressing and truing device for shaping the grinding wheel to the necessary contour.

With the foregoing and other objects in view, as will become apparent as the description proceeds, my invention consists in the elements, combinations and details of construction hereinafter described and claimed and illustrated in the accompanying drawings, wherein:

Figure 1 is a plan view of a grinding machine embodying the invention, the work-holding jig being omitted.

Fig. 2 is a side elevation of the parts shown in Fig. 1.

Fig. 3 is a vertical sectional view taken just to the left of the grinding wheel, the machine being shown in the act of grinding the profile face of a cutter.

Fig. 4 is a sectional view on the line 4—4 of Fig. 3, looking in the direction of the arrows.

Fig. 5 is a sectional view on the line 5—5 of Fig. 3.

Fig. 6 is a section on the line 6—6 of Fig. 3.

Fig. 7 is a view similar to Fig. 5, the

grinding wheel being shown in a somewhat different relation to the cutter tooth.

Fig. 8 is a view similar to Fig. 6, showing the parts in the position corresponding to Fig. 7.

Fig. 9 is a plan view of the work-holding jig, showing a cutter in position to be ground.

Fig. 10 is a front elevation of the parts shown in Fig. 9.

Fig. 11 is a section on the line 11—11 of Fig. 9.

Fig. 12 is a section on the line 12—12 of Fig. 9.

Fig. 13 is a perspective view of the templet used for grinding a cutter of the shape shown in Figs. 9 and 10.

Fig. 14 is a perspective view of the wheel 70 truing device in position for truing the grinding wheel.

Fig. 15 is an enlarged vertical sectional view of the truing device.

Fig. 16 is a perspective view of the rest 75 support.

Fig. 17 is a perspective view of the guide sleeve.

Fig. 18 is a perspective view of the truing guide sleeve.

Fig. 19 is a perspective view of the rest.

Figs. 20 and 21 are diagrammatic views illustrating the positioning of the truing guide.

The principle of operation of the machine 85 constituting the present invention is similar in many respects to that of the machines shown and described in the prior patents referred to above. The machine comprises generally a grinding wheel of any suitable

abrasive material mounted on a flat table which is provided with a guide having a contour, in horizontal section, identical with the contour of a horizontal section of the grinding wheel taken at the grinding point.

The cutter, or other article to be ground, is rigidly held in a suitable jig freely slidable over the work table and provided with a suitable templet which may coöperate with

the guide for bringing the cutter into the 90 proper relation with the rotating grinding wheel for accurately reproducing the templet form as the contour of the profile face

of the cutter teeth.

95

100

In the drawings, the numeral 21 designates any suitable pedestal for supporting the flat work table 22 which carries the upright support or grinding wheel head 23, the latter preferably being accurately positioned by dowel pins 24 and fastened in place by a suitable screw 25. The wheel slide 26 is carried in an aperture in said head and is slidable therein at a small angle 10 to the horizontal (see Fig. 3). Said slide is provided with a pair of forwardly projecting and relatively closely adjacent yoke arms 27 which support the wheel shaft 28 carrying a suitable grinding wheel 29 provided with a hub 30 rotatably mounted on said shaft as by ball or other antifriction bearings. Suitable means may be provided for rotating said wheel, as, for example, a belt (not shown) coöperating with a pulley 20 portion 30' formed on said hub. The wheel slide may be adjusted by means of a feed screw 31 actuated by a suitable graduated feed knob 32, and is held in adjusted position by a binder screw 33 which may for 25 convenient operation be provided with a handle 34. A suitable guard 35 is preferably provided for covering the grinding wheel, and, as in the prior patents above referred to, a rest 36 is provided for supporting the cutter tooth or other article to be ground. This rest, as shown, is supported by a post 37 whose lower end is seated in an aperture 38 in the table.

As will be seen, the means above described 35 for supporting the grinding wheel are such as to leave the sides of the wheel relatively unobstructed, so as to permit an increased freedom of movement of the work on both sides of the wheel, thereby facilitating the 40 grinding of profiles having sharp curves and reentrant angles.

The numeral 39 (see Figs. 3 and 17) represents guiding means, preferably in the form of a sleeve having a cross section corresponding to the horizontal section of the wheel at the grinding point. This sleeve may be attached to the table in any desired manner, but it has been found convenient and satisfactory to form it with a tapered 45 bore for receiving the preferably tapered stud portion 40 of the rest supporting post 37. The guide sleeve 39 may be further located and held against rotation by a pin 41 having a recess for receiving a corner 50 of said sleeve (see Figs. 3, 6, and 14). This construction has the advantage of permitting the ready removal of a guide sleeve and the substitution therefor of another sleeve having a different cross section. 55 These parts are preferably so positioned that the guide sleeve is in exact vertical alinement with the grinding wheel at the grinding point.

Means are provided for supporting the 60 cutter or other article to be ground, and

for bringing it into proper relation to the grinding wheel, said means, as herein shown, comprising a work support or work-holding jig 50 which, as shown in Figs. 9 to 12, consists of a pair of standards 51 and 52 connected by a base 53 carried by a plurality of supporting feet preferably in the form of adjustable supporting screws 53'. Carried by the standards 51 and 52 is a work-holding arbor 54 adapted to receive thereon the cutter or other work 56, which arbor may have a flange 55, against which one end of said cutter 56 bears, and a collar 57 adjustable thereon for holding the cutter against said flange. The ends of 80 the arbor are provided with journals 58 and 59 which, as shown in Figs. 9 and 11, are provided with transverse alined slots 60 and 61. These journals fit snugly in slots 62 and 63 in the upper ends of the standards 51 and 52 respectively. The slots 60 and 61 receive cylindrical studs 64 and 65 rigidly carried, eccentric to the arbor, by blocks 66 and 67 firmly attached to the standards, as by screws 68. The arbor may 90 be adjusted longitudinally and clamped in adjusted position by means of adjusting screws 70 and 71 bearing on opposite ends of said arbor at the inner ends of the slots 62 and 63, said screws passing axially 95 through and having threaded engagement with the studs 64 and 65, respectively. The arbor is adjusted vertically and maintained in its position of adjustment by means of an adjusting screw 73 suitably guided for non-rotative vertical movement in an opening in the standard 52 and engaging at its upper end the journal 59, said screw having a threaded portion to receive an adjusting nut 74 located in an aperture in said standard. It is necessary to provide but one such adjusting and supporting screw, since, when 100 said screw is operated to raise or lower the journal 59, engagement of the eccentric stud 65 with the slot 61 will cause simultaneous 105 rotation of said journal in its bearing slot 63, and the consequent rotation of the journal 58 in its bearing slot 62 will cause said journal 58, by reason of engagement of the stud 64 with the slot 60, to be raised and lowered in unison with the journal 59, and to the same extent, thereby maintaining the 110 parallelism of the arbor with the work table.

As in the construction shown in the prior 115 patents above referred to, the arbor is so adjusted that its axis is normally in the horizontal plane of the top of the rest 36 when the jig is in operative position for grinding the profile face of a cutter.

When a cutter tooth of ordinary shape 120 is reduced in height by the process of grinding the profile face, the face is widened on account of the inclination of the back of the tooth. If this widening of the profile 125 face is carried beyond a certain limit, the 130

cutter becomes unserviceable because the back edges of the profile faces of the teeth will project more than the front or cutting edges. It will become necessary, therefore, 5 to narrow the face of each tooth by grinding away the back portion thereof. The jig described above is especially adapted for this purpose since, as above explained, by turning the nut 74 the arbor 54 may be 10 raised thereby bringing the back edge of the profile face of each tooth into a position where it may be reached and suitably ground down by the grinding wheel.

Means are provided for bringing the 15 work into the proper relation to the grinding wheel, said means, as herein shown, comprising a suitably formed templet 75 held parallel to the arbor and work table in opposed grooves 66 and 77 formed in the 20 lower ends of the standards. For the purpose of suitably and adjustably supporting the back face of the templet there is provided a pivoted adjusting bar 78, preferably mounted on pivot pins 79 in the standards. 25 This bar may be adjusted transversely by means of a suitable adjusting screw 80. The templet is held against the bearing face of said bar by a clamp bolt 81, having a nut 82 and an inclined lug 83 receivable in a 30 corresponding slot 84 in the templet. This provides a convenient construction for adjustably securing the templet in the proper relation to the cutter.

The peripheral edge of the grinding 35 wheel is so shaped and positioned that a horizontal section thereof taken through the wheel at the top of the rest, *i. e.*, the grinding point, corresponds exactly in contour with the plan or horizontal section of 40 the guide sleeve 39, and lies in exact vertical alinement therewith.

Means are provided for forming the wheel with this section, such means being preferably as follows. The numeral 90 (see Figs. 45 14 and 15) refers generally to such a wheel-truing device which may consist of a bottom plate 91 supported by adjustable feet 92 and carrying a vertical threaded standard 93 located in a recess in the truing block 94 and 50 supporting the latter at various points of vertical adjustment by means of the adjusting nut 95. The truing block is held against rotation by a guide pin 96 secured in the plate 91 and is positioned further by a guide 55 screw 97 which passes through the plate 91 from the under side and engages a threaded opening in the block 94. For cutting the grinding wheel to the desired form, there is provided a dressing tool or member 98, preferably a diamond, mounted in a carrier 99 adjustable in a recess 100 in the truing block, and beneath which a second recess or pocket 101 may be conveniently provided in said block for collecting the abrasive material 65 removed from the wheel. The carrier 99 may

be held in adjusted position by a pair of aligned clamping pins 102 the inner of which engages said carrier, and the outer of which is acted upon by a clamping screw 103. The adjacent or interengaging ends of these 70 clamping pins are preferably formed convex, as shown, which allows the lower pin to bear evenly on the carrier. At its lower front portion, the block 94 is provided with guide lugs 104 which coöperate with the cylindrical 75 sides of an oblong truing guide sleeve 106, which has an aperture 107 for receiving an eccentric portion 37^a of the rest support 37, as shown in Fig. 14. The under side of the truing guide sleeve is formed with a central 80 recess terminating, at opposite sides of the aperture 107, in shoulders 108 and 109, which are so formed and located as to snugly seat on the guide sleeve 39. In order to insure this snug seating without lost motion, the 85 shoulders 109 are preferably slightly inclined. The cylindrical sides of the sleeve 106 are formed of the same curvature as the faces of the guide sleeve 39, and when said sleeve 106 is seated on the sleeve 39, as above 90 explained, one of said sides occupies a position approximately parallel to the adjacent face of said sleeve 39, thereby providing an extended bearing surface which may be followed by the lugs 104 to cause the diamond 95 or other dressing member 98 to move in a path parallel to said face and consequently true the edge of the wheel by bringing the same into conformity with the configuration of the sleeve 39. The relative positions of 100 the guide sleeve 39 and truing sleeve 106 will be clear from Figs 20 and 21, which illustrate diagrammatically the positions of the truing sleeve for dressing the opposite sides, 105 respectively, of the wheel.

In grinding cutters it is necessary, in order to obtain the necessary clearance angle on the teeth, that the grinding take place at a point below the horizontal diameter of the grinding wheel, and the top of the rest 36 is correspondingly located, as will be clear from Fig. 3. As the truing of the wheel is effected on its horizontal diameter, the surface of the truing guide sleeve is not exactly in alinement with that of the guide sleeve 39, but is slightly displaced in the direction away from the wheel axis. This displacement is secured by forming the portion 37^a eccentric to the taper portion 40. The amount of this eccentricity is exactly equal 110 to the difference between the radius of the grinding wheel and half of its horizontal chord at the grinding point.

In order to accurately position the diamond 98 there may be employed a setting rod 105 normally kept in a recess in the grinding wheel head, as shown in Fig. 2. With the aid of this rod the diamond may be accurately located with respect to lateral adjustment.

While the form of mechanism herein shown and described is admirably adapted to fulfil the objects of the invention, it is to be understood that said invention is by no means limited to the particular construction herein disclosed, but is susceptible of embodiment in various other forms within the scope of the claims hereunto appended.

Having thus described my invention, I 10 claim:

1. A machine for grinding irregular profiles comprising a table, an upright support fixed thereon, a transverse slide carried by said support and provided with a pair of 15 forwardly projecting arms, a screw for adjusting said slide in said support, a shaft carried by said arms, and a grinding wheel rotatably mounted on said shaft between said arms.
2. A machine for grinding irregular profiles comprising a table, a support fixedly mounted thereon, a pair of arms adjustably carried by said support, a grinding wheel between said arms and carried thereby, a 25 guide member in fixed relation to said table, and a templet movable over said table in engagement with said guide member.
3. A machine for grinding irregular profiles comprising a table, a support fixedly 30 mounted thereon, a pair of arms adjustably carried by said support, a grinding wheel between said arms and carried thereby, a guide member in fixed relation to said table, a jig provided with means for holding the 35 article to be ground, and a templet carried by said jig and positioned to be engageable with said guide member.
4. A machine for grinding profile faces of formed cutter teeth comprising a table, 40 a grinder supported above said table, a rest for cutter teeth, and a guide sleeve carried by said rest.
5. In a machine for grinding the profile faces of formed cutter teeth, the combination 45 with a grinding wheel, of a work support, a bodily movable arbor, and means for maintaining the parallelism of the arbor with the work support when the arbor is moved.
6. In a machine for grinding the profile faces of formed cutter teeth, the combination 55 with a grinding wheel, of a work support having an arbor disposed with its axis transverse to the periphery of said wheel, grinding means for said work support including a templet parallel to the axis of said arbor, said arbor being bodily movable with respect to said templet, and means for preserving the parallelism of said arbor and 60 templet.
7. A work-holding jig for grinding machines comprising a pair of standards, an arbor vertically movable in said standards, and means for maintaining the parallelism

of the arbor with the jig when the arbor is 65 vertically moved.

8. In a machine for grinding the profile faces of formed cutter teeth, the combination 70 with a vertically disposed grinding wheel, of a horizontally and vertically movable arbor disposed transversely to said grinding wheel for presenting work thereto, and means for maintaining the parallelism of said arbor when the same is vertically moved.

9. A work-holding jig for grinding machines comprising an arbor having ends 75 provided with transverse slots, supporting standards formed with slots for receiving the ends of the arbor, and eccentric studs 80 carried by the standards and received in the slots in the arbor.

10. A work-holding jig for grinding machines comprising an arbor having ends provided with transverse slots, supporting 85 standards formed with slots for receiving the ends of the arbor, eccentric studs carried by the standards and received in the slots in the arbor, and means for raising and lowering said arbor.

11. A work-holding jig for grinding machines comprising an arbor having ends 90 provided with transverse slots, supporting standards formed with slots for receiving the ends of the arbor, eccentric studs carried by the standards and received in the slots in the arbor, and blocks rigidly secured to said standards and by which said studs are carried.

12. A work-holding jig for grinding machines comprising an arbor having ends provided with transverse slots, supporting standards formed with slots for receiving the ends of the arbor, eccentric studs carried by the standards and received in the 105 slots in the arbor, and an adjusting screw carried by one of said standards and engaging one end of said arbor for raising and lowering the same.

13. A work-holding jig for grinding machines comprising an arbor having ends 110 provided with transverse slots, supporting standards formed with slots for receiving the ends of the arbor, eccentric studs carried by the standards and received in the slots in the arbor, and adjusting screws carried by said standards and engaging the inner ends of said last named slots for longitudinally adjusting said arbor.

14. A work-holding jig for grinding machines comprising an arbor, supporting standards therefor having opposed grooves, a templet slideable in said grooves, an adjustable bar against which said templet bears, and means for holding said templet 120 against said bar.

15. A work-holding jig for grinding machines comprising an arbor, supporting

standards therefor, opposed grooves in said standards, a templet slideable in said grooves and provided with a recess, an adjustable bar against which said templet bears, and a 5 bolt formed with an inclined lug received in said recess for holding said templet against said bar.

16. A machine for grinding irregular profiles comprising a table, a grinding wheel supported above said table, a supporting 10 post fixed to said table, and a guide sleeve carried by said post.

In testimony whereof I affix my signature.
WILLIAM O. BARNES.
